UNITED STATES PATENT OFFICE

2,061,345

POWER HAMMER

Emmons R. Boddingtonhouse, Chicago, Ill., assignor
to Gas Tool Patents Corporation, Chicago, Ill.,
a corporation of Delaware

Application November 9, 1934, Serial No. 752,307

3 Claims. (Cl. 123—7)

This invention pertains in general to power hammers and is shown for illustrative purposes as embodied in a hammer of the internal combustion type disclosed in the Mould Patent No. 5 1,868,754. The mode of operation with respect to ignition, carburetion and starting, is substantially that described in said Mould patent. The invention resides particularly in the anvil and its mounting.

10 One important feature of the invention resides in a construction which enables the downward thrust of the piston return springs to be exerted against the tool guide rather than against the tool itself, thereby minimizing the strain on the 15 springs and permitting the delivery of a more effective blow upon the tool.

In many of the prior power hammers in which the piston return springs were supported on the anvils, the design of these anvils and anvil housings has been such that fragments of broken 20 springs were often able to become lodged underneath seating surfaces of the anvils and thus introduce a danger of defective operation and fracture of the parts. My present invention eliminates this danger by an anvil design which 25 prevents spring fragments from interfering with the proper operation of the anvil.

Other objects and advantages of the invention which are inherently possessed by it will be discussed and disclosed hereinafter.

30 In the drawings:

Fig. 1 is a side elevation showing the preferred construction of a gas hammer in which these improvements are to be embodied;

35 Fig. 2 is a partial vertical section of such a hammer showing one improved form of anvil; and

Fig. 3 is a partial vertical section showing another form of anvil provided by this invention.

40 Referring further to the drawings, the hammer shown in Fig. 1 comprises a cylinder provided exteriorly with a plurality of radially disposed longitudinally extending fins 1 affording provision for the rapid dissipation of heat generated 45 within the cylinder. Below the cylinder is an anvil housing 2 separated from the cylinder casting 3 by means of an insulating gasket 4. At the top of the fins and resting thereupon is a handle supporting member 5 and secured thereupon at opposite sides are a pair of handles, one of which, designated 6, is shown. These are the handles which the operator grasps for holding the gas hammer.

50 Below the anvil housing 2 is a tool guide 7 which houses the upper end of a tool such as a drill 8,

The tool guide 7 is slidably mounted on a pair of rods 9 and 11 which are provided with nuts at their lower ends against which are seated compression springs 12 and 13. The upper ends of these springs rest against shoulders as shown on 5 the tool guide 7. The rods 9 and 11 extend upwardly through the anvil housing, seating thereagainst by means of shoulders 14 and 15 which cooperate with corresponding recesses in the anvil housing to prevent the latter from slipping downwardly on the rods. The upper ends of these rods 10 extend through the handle supporting member 5 and are secured thereupon by means of nuts 16 and 17. Through the cooperation of the circumferential shoulders 14 and 15 and the nuts 15 16 and 17 the rods 9 and 11 hold the anvil housing firmly secured against the bottom of the cylinder casting. The tool guide, however, is free to slide upwardly and downwardly on these rods and is yieldingly held against the bottom of the 20 anvil housing by means of the springs 12 and 13.

Referring particularly to Fig. 2, an anvil 18 is disposed in the anvil housing and provided with an enlarged lower end 19, the upper shoulder of which seats against a cooperating shoulder in 25 the anvil housing for limiting upward movement of the anvil. The upper portion 21 of the anvil is of reduced diameter so as to provide a shoulder 22 upon which the piston return springs are seated. Preferably the return springs consist of 30 two springs arranged in series, the lower spring 23 being the shorter and heavier spring while the upper spring 24 rests upon the cushion spring 23 and abuts the top of a recess 25 in the piston 26. A depending portion 27 of the piston 35 constitutes the striking portion of the piston which upon downward movement of the piston induced by explosion of a combustible mixture or otherwise is caused to impact the top of the anvil extension 21.

40 The cooperating shoulders of the anvil and its housing being separated from the piston springs by a portion of the anvil body between which and the surrounding housing sliding clearance only is provided, it will be apparent that broken piston 45 spring particles are precluded from lodging between said shoulders and damaging the apparatus. While such spring breakage is rare, the damage occasioned by the lodgment of spring particles between the opposed shoulders of the 50 anvil and housing in apparatus permitting entrance of such spring particles has been serious.

In the normal operation of the device shown in Fig. 2 the blow of the piston will ordinarily be absorbed directly through the anvil 18 upon the 55

drill 8. However, should the drill be lifted from the work temporarily by the operator while the hammer is running, the anvil blows will be absorbed by the tool guide 7 whose heavy supporting springs 12 and 13 are amply able to cushion these shocks.

In the embodiment of the invention shown in Fig. 3, the anvil consists of an outer sleeve generally indicated as 31 and an inner striking pin 32 which has a sliding fit within the sleeve. The upper end 33 of the sleeve provides the supporting seat for the piston springs. These springs may be one or more in number and in the illustrated embodiment include a cushion spring 34 and a main return spring 35, the latter being disposed between the cushion spring and the opposed surface 36 of the piston 31. The striking portion 38 of the piston in its working stroke imparts a blow to the striking pin 32 of the anvil 20 and thence to the tool 40.

It will be noted that a shoulder 41 on the sleeve of the anvil cooperates with a corresponding shoulder on the anvil housing 42 to limit the upward movement of the anvil sleeve. This shoulder is spaced from the spring supporting shoulder 33 so that it is protected from spring fragments which would interfere with the proper seating of the anvil sleeve.

The lower edge 43 of the anvil sleeve rests directly upon the tool guide. Hence, when the explosion drives the piston downwardly and the cylinder and associated parts are simultaneously driven upwardly, the upward movement of the tool guide 7 and sleeve 31 is resisted with progressively increasing effort by the springs 34—35 as they are compressed by the piston. This resistance imposes a compression strain upon the tool guide supporting springs 12 with the result that a snubbing action against the rise of the cylinder is produced, which causes the tool to operate quieter, steadier, smoother, and more efficiently and with less vibration transmitted to the operator.

The down or working stroke of the piston necessarily compresses the return springs and in constructions of the type exemplified by Fig. 2 wherein the spring force is transmitted to the tool there exists a tendency for this force to impart an initial movement to the tool before it receives the impact from the piston, consequently the effectiveness of the blow is somewhat deadened.

In the construction of Fig. 3 the force of the piston springs under compression is transmitted by the sleeve portion of the anvil, not to the tool but to the tool guide. The tool therefore remains in its uppermost position to receive the full impact of the blow under which the most effective stroke of the tool is delivered.

Furthermore, should the stroke of the anvil under impact thrust the lower end of the anvil piece 32 against the tool guide 7 with sufficient force to drive this guide away from the lower end of housing 42 against which it is yieldingly held by springs 12 and 13, the sleeve piece 31 of

the anvil will travel with the piece 32 and the guide 7, thereby relieving the piston springs from further and undue compression which would be likely to result in breakage.

In ordinary operation the weight of the entire apparatus will be carried by the tool 40 which will push the striking piece 32 upwardly into the anvil sleeve into the position shown in Fig. 3.

Should the hammer be lifted temporarily from the work, the enlarged head 44 of the striking piece 32 will strike the tool holder 7 and the shock will then be absorbed through the compression springs such as 12 or 13.

While I have shown in the drawings and described the preferred embodiments of my invention, it is to be understood that I do not intend thereby to be limited to the particular forms disclosed, but aim to cover all modifications and alternative constructions falling within the spirit and scope of the invention as expressed in the appended claims.

I claim:

1. In an impact tool of the explosive type, the combination of a cylinder, a piston hammer reciprocable therein, a housing in alignment with said cylinder, a two piece anvil in said housing comprising an impact portion aligned to receive the blow of said hammer and a surrounding sleeve, a tool guide against which the outer end of said sleeve abuts, spring means interposed between said piston hammer and the inner end of said sleeve by which driving force of said piston on its working stroke is transmitted through the intermediary of said sleeve to said tool guide, and means yieldably securing said tool guide to said housing whereby the downward piston thrust against the tool guide is caused to snub the upward thrust of the cylinder resulting from the explosion in the cylinder.

2. In an impact tool of the explosive type, the combination of a cylinder, a piston hammer therein, an anvil member positioned to receive the hammer blow, and means for yieldably resisting the upward thrust of said cylinder resulting from the explosion therein, said means comprising a tool guide beneath said cylinder, a sleeve surrounding said anvil member and engaged at its lower end with said tool guide, a piston return spring interposed between the upper end of said sleeve and said piston and means for yieldably connecting said tool guide to said cylinder.

3. An impact tool of the explosive type comprising a cylinder and an explosion actuated impact delivery member reciprocable therein, a spring for returning the same, a tool guide, a tool guided thereby, means for transmitting the delivered impact from said member to said tool, means interposed between said spring and said tool guide for transmitting the spring thrust to said guide, and means yieldably connecting said tool guide to said cylinder whereby the thrust of the cylinder induced by the explosion is yieldingly snubbed.

EMMONS R. BODDINGHOUSE. 65
